UNITED STATES PATENT OFFICE.

MONROE GUETT, OF HARTFORD, CONNECTICUT, ASSIGNOR TO HART & HEGEMAN MANUFACTURING COMPANY, OF HARTFORD, CONNECTICUT, A CORPORATION OF CONNECTICUT.

ELECTRIC SWITCH.

1,028,350.

Specification of Letters Patent. Patented June 4, 1912.

Application filed September 20, 1910. Serial No. 582,835.

To all whom it may concern:

Be it known that I, MONROE GUETT, a citizen of the United States, and a resident of Hartford, in the county of Hartford and 5 State of Connecticut, have invented certain new and useful Improvements in Electric Switches, of which the following is a specification.

The invention relates particularly to 10 switches of the push-button type, and the object of the invention is to produce a switch of the character described having features of novelty and advantage. A straight line of the push buttons is provided, and also there is provided a mechanism whereby the poles, though they have 15 an oscillatory movement between two extreme positions, can be moved and stopped at intermediate positions in order that the 20 switch can be used to control separate circuits.

Referring to the drawings: Figure 1 is a side view of the switch mechanism the poles being removed. Fig. 2 is a side view in reverse of Fig. 1. Fig. 3 illustrates in side and end view the pole operating mechanism. Fig. 4 is a view of one of the poles plates. Fig. 5 shows in edge and side view the pinion and pawl releasing device. Fig. 6 shows 30 in side and end view the switch frame.

a denotes the supporting bar of the switch apertured to receive the push buttons *b*, and *c* denotes in general a frame plate secured to the supporting bar.

35 *b' b'* are racks secured to the push buttons slotted as at 1, 1, to receive the guiding studs 2, 2, on the frame plate *c*.

d is a pinion mounted on the spindle 5 in a mesh with the two racks *b' b'*. This 40 pinion carries a spring arm 6 which lies between the crossed arms of a spring 7.

e denotes what may be termed a pole-plate to which one of the poles of the switch plates 10 is secured, this pole-plate having a spring 45 arm 11, which lies over the spring arm 6 on the pinion, and between the ends of the spring 7, and at its opposite end enters an aperture 12 in the second pole or switch plate 15, so that the two switch plates will 50 move together. This pole-plate *e* has pivoted to it two pawls 16—17 which are adapted to cooperate with stop shoulders 16^a 16^b 16^c 17^a 17^b 17^c on the frame plate *c*, and they are held in engaging positions by the

springs 18—19. The pinion carries a 55 knock-off lug 20 which is adapted to engage either one of the pawls 16—17 to disengage it from its stop.

If the right hand push button in Fig. 1 be pressed down it will be seen that the 60 knock-off lug 20 will be moved to the left until it comes in contact with the pawl 16, which will be moved out to disengage it from the stop 16^b which it engages, and upon this disengagement the spring which 65 has been tense during this movement of the pinion, will throw the switch plates to the positions shown in Fig. 2, the switch plate in Fig. 1 being illustrated in dotted lines. If now the right-hand push button be 70 pressed down the knock-off lug 20 will engage the pawl 16, disengage it from its stop 16^a, and the spring will throw the switch plates until the pawl 16 comes into engagement with the stop 16^a. This represents the 75 intermediate position of the switch plates. Further pressure on the right-hand push button will cause the knock-off lug 20 to disengage the pawl 16 from the stop 16^a when the spring will throw the switch plates 80 still farther around until the pawl comes into engagement with the stop 16^c. Of course the stops 16^a and 17^c are not necessary as the spring arm 6 coming against the ends of the slot *c'* in the frame plate will form 85 a suitable stop for one of the extreme positions of the switch plates.

It is of course apparent that the rack and pinion mechanism can be utilized with the ordinary forms of push button switches.

I claim:

1. In an electric switch of the push button type, a frame plate having a plurality of stops, a pole plate mounted on the spindle and connected to move with said poles, swinging pawls pivoted on the pole plate and adapted to engage the stops on the frame plate, a pinion mounted on the spindle and adapted for movement independently of said pole plate and poles, a spring connecting said pinion with said poles, a knock-off lug on said pinion adapted for engagement with said pawls, a driving connection between the push buttons and said pinion.

2. In an electric switch of the push button type, the combination with a supporting bar, a frame plate, the latter having two sets

of oppositely disposed stops, a spindle supported in the frame plate, the poles mounted on said spindle, a pole-plate connected to move with said poles, pawls pivotally supported on said pole-plate, one adapted for co-operation with one set of said stops, and one with the other set, an operating member mounted on the spindle, a spring connecting said operating member with said poles, a knock-off lug on said operating member adapted for co-operation with said pawls, a driving connection between the push buttons and said operating member.

3. In an electric switch of the push button type the combination with the supporting bar, a frame plate and spindle supported by the frame plate, the frame plate having a plurality of stop shoulders on each side of said spindle, poles mounted on the

spindle, a pole-plate mounted on the spindle and connected to move with said poles, pawls pivoted on said pole-plate, a spring tending to hold said poles in engagement with the stops on the frame plate, and an operating member mounted on the spindle and adapted for movement independently of the poles, a spring connecting said operating member and said poles, a knock-off lug actuated by said member and adapted to engage said pawls to disengage them from said stops, and a driving connection between said operating member and push buttons.

MONROE GUETT.

Correction in Letters Patent No. 1,028,350.

It is hereby certified that in Letters Patent No. 1,028,350, granted June 4, 1912, upon the application of Monroe Guett, of Hartford, Connecticut, for an improvement in "Electric Switches," an error appears requiring correction as follows: In the grant, name of assignee, lines 8 and 16, for "Hart & Hageman Manufacturing Company" read *Hart & Hegeman Manufacturing Company*; and that the said Letters Patent should be read with this correction therein that the same may conform to the record of the case in the Patent Office.

Signed and sealed this 16th day of July, A. D., 1912.

C. C. BILLINGS,
Acting Commissioner of Patents.

of oppositely disposed stops, a spindle supported in the frame plate, the poles mounted on said spindle, a pole-plate connected to move with said poles, pawls pivotally supported on said pole-plate, one adapted for co-operation with one set of said stops, and one with the other set, an operating member mounted on the spindle, a spring connecting said operating member with said poles, a knock-off lug on said operating member adapted for co-operation with said pawls, a driving connection between the push buttons and said operating member.

3. In an electric switch of the push button type the combination with the supporting bar, a frame plate and spindle supported by the frame plate, the frame plate having a plurality of stop shoulders on each side of said spindle, poles mounted on the

spindle, a pole-plate mounted on the spindle and connected to move with said poles, pawls pivoted on said pole-plate, a spring tending to hold said poles in engagement with the stops on the frame plate, and an operating member mounted on the spindle and adapted for movement independently of the poles, a spring connecting said operating member and said poles, a knock-off lug actuated by said member and adapted to engage said pawls to disengage them from said stops, and a driving connection between said operating member and push buttons.

Correction in Letters Patent No. 1,028,350.

It is hereby certified that in Letters Patent No. 1,028,350, granted June 4, 1912, upon the application of Monroe Guett, of Hartford, Connecticut, for an improvement in "Electric Switches," an error appears requiring correction as follows: In the grant, name of assignee, lines 8 and 16, for "Hart & Hageman Manufacturing Company" read *Hart & Hegeman Manufacturing Company*; and that the said Letters Patent should be read with this correction therein that the same may conform to the record of the case in the Patent Office.

Signed and sealed this 16th day of July, A. D., 1912.
